HOSPITAL BED CRANE

Filed April 23, 1932

INVENTOR.

Fred Scheidegger,

BY

John Stearns
ATTORNEY

UNITED STATES PATENT OFFICE

FREDERICK SCHEIDEGGER, OF SCHENECTADY, NEW YORK

HOSPITAL BED CRANE

Application filed April 23, 1932. Serial No. 607,140.

This invention relates to apparatus for lifting invalids or bedridden persons and its object is to provide a crane of this class which may be supported on a bed, will be adapted to beds of different lengths and constructions, and by which a person of but moderate strength may lift a patient of any weight, and which also will be as little as possible in the way of the attendant in attending the patient.

In the drawing,

Fig. 1 is a side elevation, showing the apparatus in operative position on a bed;

Fig. 2 is a plan thereof;

Fig. 3 is an enlarged plan view of the mid-portions of the four bars of the supporting structure, disconnected with each other;

Fig. 4 is an enlarged side elevation of the lower end of a bar and its securing means;

Fig. 5 shows a fragment of such lower end with said means removed;

Fig. 6 is a section on line 4—4, Fig. 1, with a certain tube 14 also shown in section; and

Figs. 7 and 8 are a side elevation and a plan of a certain folding beam.

In the drawing 1 is a bed frame, as of an iron bed of the ordinary hospital type. To the bed frame is attached the supporting structure 1 of my apparatus, which structure is arched as seen in side elevation (Fig. 1) and substantially X-shaped as seen in plan (Fig. 2).

Said structure is constructed as follows: 2—2 designates a pair of bars each of which is formed with each end portion thereof preferably straight but so that with one end portion in horizontal position the other end portion will be offset to one side of the axis of the first-named end portion and project downwardly, the bend in each bar being preferably a curve; as to one bar the offsetting of the downwardly projecting portion is to one side and that of the other to the other side of said axis. Each bar has

preferably a top longitudinal flange 2a at the outer side thereof, as by forming the bars of angle iron. The horizontal end portions of the two bars are secured rigidly together, so that their flanges 2a form a channel 3 open at the top, by tie pieces 4, which

may be bolted or riveted to them as shown. Between the flanges said horizontal portions of the bars are formed with a longitudinal slot 5, and they also have a longitudinal series of holes 6.

7—7 designates two other such flanged bars formed in the same manner as the bars 2. The horizontal end portions of these bars lap under the horizontal end portions of the bars 2—2, projecting reversely thereto their flanges 7a lapping outwardly of the flanges 2a of the bars 2—2, and they also have a longitudinal series of holes 9.

Bolts 10 having nuts 11 clamp the horizontal ends of the bars 2—2 to those of the bars 7—7; they are received by four of the holes 6 and 9, depending on the length which the supporting structure is to have according to the length of the bed. I thus have a structure which in plan is formed with several legs all diverging from a common center and having their end portions diverted downwardly so that in side elevation said structure is arched; in the preferred form, as shown, there are four legs.

The downwardly diverted end portion or extremity of each leg is provided with a row of notches 12, here in pairs of which one in each pair is formed in the main web and the other in the flange of the bar. Any pair of these notches, according to the height required for the supporting structure, is to receive a pin or bolt 13 which loosely penetrates a tube 14 slipped over the leg. This tube is secured to a leg 1a of the bed by a clamp comprising two clamp members 15, which have curved end portions (Fig. 6) to embrace the tube and the bed-leg, and a bolt 16 and wing-nut 17 connecting them. There are preferably two tubes, pins and clamps to support the structure 1 at the head of the bed, as shown in Fig. 1.

At 18 is a pin which traverses the slot 5 and rests on the bars 2—2 between their flanges. It carries a hook 19 which supports a block-and-fall 20 provided with a hook 20a and whose rope 20b may be tied to the bed to support any load assumed by the

block-and-fall. These parts form a lifting tackle.

A lift to immediately support the patient is shown comprising pivoting devices 21, 5 two U-shaped bails 22 each having its extremities pivoted on the devices 21 and also formed with loops 23, and a flexible stretcher 24, as of duck, connecting the lower portions of the bails. So much follows the construction set forth in my Patent No. 1,760, 10 443 and requires no further description. The corresponding loops of the bails are here connected by straps 25. These straps extend over a beam 26, resting in the notches 26a thereof, which thus supports the lift and the beam itself is supported by a bent rod 27 whose ends are hook-shaped and engage in holes 28 in the beam and which is hung in the hook 20a of the tackle 20. The 15 lift, beam and rod thus form a sling. I do not wish to be limited to the particularly described bail part of this sling nor in fact to the other details thereof, although an important feature of the described sling is 20 a beam, as 26, in that as shown such beam makes it possible to support the whole length of the patient, attention being called to the bandages or equivalent 29 which may be used with the lift or equivalent (which supports the torso of the patient, as shown) to 25 support the patient's head and legs.

The beam as shown may be folded to shorten its length (as in supporting a child). Thus in Figs. 7 and 8 it is shown 30 in two sections 26w hinged together at 26a so that the two sections may be folded together face to face, there being a hook 26y pivoted on one section and a stud 26z to be engaged by the hook to hold the sections 35 in extended relation, as in these figures.

Since the supporting structure is formed as seen in plan with several legs all diverging from a common center and having their 40 end portions diverted downwardly, so that 45 said structure as seen in side elevation is arched, said structure has the necessary strength for supporting any load required of it and it affords the necessary clearance for a person, as the physician or nurse, serving 50 the patient and having occasion to lean over the bed at either side or the head or foot thereof for any purpose. It is furthermore adjustable at its top mid-portion to suit the length of the bed and also to suit 55 certain variations in width, to wit, by springing its legs at the head or foot of the bed together or apart; and it is also adjustable up or down by changing each bolt 13 so as to engage the pair of notches 12 at 60 the required height. There is also adjustability of the tackle and the sling lengthwise of the bed, due to slot 5.

I do not wish to be limited to the legs of the supporting structure being each secured 65 specifically to a leg of the bed, although that

is the preferred construction since it permits a substantial engagement of said structure to be had, using some such simple form of securing means as that afforded by the device shown best in Fig. 6.

Having thus fully described my invention what I claim is:

1. In combination, with a bed frame having legs, a supporting structure extending over the frame and having downwardly extending legs adjoining legs of the bed frame, each leg of said structure being notched, a tube receiving the notched portion of each leg of said structure, a pin penetrating the tube and engaged in the notch, and means to clamp each tube to the corresponding leg of the bed frame. 75

2. In combination, with a bed, a supporting structure comprising two members each having one end portion over the bed and channelled and the remaining portion thereof bifurcated and each branch of the latter portion L-shaped in cross section and forming a continuation of the corresponding L-shaped half cross-section of the channelled portion, one channelled portion being received in the other, and means to secure said channelled portions together, the branches of each bifurcated portion being spread apart and bent downwardly, and means to 80 secure each branch to the bed. 90

3. In combination, with a bed, a supporting structure having a channelled mid-portion over the bed and each of its end portions bifurcated and each branch of the latter portion L-shaped in cross section and forming a continuation of the corresponding L-shaped half cross-section of said channelled portion, the branches of each bifurcated portion being spread apart and bent downwardly, and means to 95 secure each branch to the bed. 100

In testimony whereof I affix my signature.

FRED. SCHEIDECKER.
